(57) **CLAIM**

I claim the ornamental design for a guacamole keeper, as shown and described.

DESCRIPTION

FIG. 1 is a top perspective view of a guacamole keeper, showing my new design.

FIG. 2 is a front elevational view of the guacamole keeper, the rear elevational view being identical.

FIG. 3 is a left side elevational view of the guacamole keeper, the right side elevational view being identical; and, FIG. 4 is a top plan view of the guacamole keeper.

Portions of the guacamole keeper shown in broken lines form no part of the claimed design.
